UNITED STATES PATENT OFFICE

161,085

REFLECTOR SIGNAL

Clark M. Bolser, Cedar Falls, Iowa, assignor to
The Bolser Corporation, Cedar Falls, Iowa, a
corporation of Iowa

Application February 4, 1950, Serial No. 7,734

Term of patent 14 years

(Cl. D72—1)

To all whom it may concern:

Be it known that I, Clark M. Bolser, a citizen of the United States and a resident of the city of Cedar Falls, county of Blackhawk, State of Iowa, have invented a new, original, and ornamental Design for a Reflector Signal, of which the following is a specification, reference being had to the accompanying drawing, forming a part thereof, in which:

Figure 1 is a perspective view of a reflector signal, showing my new design, the signal being unfolded for use.

Figure 2 is a perspective view of the same showing the signal folded for storing.

Figure 3 is an end elevational view of the signal in the unfolded position; and

Figure 4 is a top plan view thereof.

I claim:

The ornamental design for a reflector signal, substantially as shown.

CLARK M. BOLSER.
